UNITED STATES PATENT OFFICE

WALTER G. BAGLEY, OF PUEBLO, COLORADO

GAS BURNER

Application filed December 3, 1928. Serial No. 323,424.

This invention relates to gas burners. It is an object of the invention to provide a gas burner adapted to emit a sheet of gaseous fuel at an angle and in intersecting relation to a stream of air.

Another object is to provide in a burner of the above stated character, an unbroken sheet of fuel in intersecting relation to the air stream. A further object is to cause the intersection to occur substantially at the point of ignition of the mixture in contradistinction to burners in which air and combustible gases are mixed before combustion.

Another object of the invention resides in the provision of a burner of the above type in which the sheet of gaseous fuel crosses the air stream at substantially right angles.

Another object is to provide a burner in which two different kinds of fuel may be caused to intersect the air stream at or near the point of ignition either singly or simultaneously in accordance with varying conditions hereinafter to be described.

A further object is to provide adjustments for varying the thickness of the sheet of fuel gas whereby to regulate its quantity proportionate to that of the air stream, and still other objects reside in details of construction and novel and beneficial arrangements and combinations of parts as will be clearly brought out in the course of the following description with reference to the accompanying drawings.

In the drawings, in the several views of which corresponding parts have been similarly designated,

Figure 1 represents a sectional elevation of a burner made in accordance with my invention, in its simplest form;

Figure 2, a similar view showing as a modification, a means for supplying the air required in the operation of the burner, under artificially applied pressure;

Figure 3, a similar view, showing means for the selective supply of either of two gaseous fuels to the burner, and showing a suitable adjustment to regulate the width of the opening through which the fuel is emitted, and

Figure 4, a similar view showing a modi-

fied construction by which two kinds of gaseous fuel may be emitted either separately or simultaneously at the will of the operator.

Referring first to Figure 1 of the drawings, the wall 5 of a furnace has an opening 6 into which the burner extends.

The burner comprises a nozzle pipe 7 connected with a header or main supply pipe 8. The header is connected with a conveniently located source for the supply of gaseous fuel and the flow of gas from the header to the nozzle pipe may be controlled by a hand-operated valve 9.

A deflector 10 mounted in spaced relation to the open end of the nozzle pipe provides a narrow annular passage 12 through which the gases are emitted.

The width of the passage must necessarily be varied in accordance with the requirements of different kinds of fuel and other varying conditions, and it is for this reason desirable that the deflector be mounted in the pipe so that its distance from the end thereof may be adjusted.

The deflector is to this end provided with radial wings 13, that engage the interior of the pipe and permit of sliding adjustment of the deflector in either direction.

The deflector is of conical form to better spread the gas for its emission through the annular outlet, and its side facing the furnace is protected from the radiant heat by a comparatively heavy head 14 of refractory material that may be strengthened by an embedded reinforcement, as shown at 15.

The end of the nozzle-pipe extends into the opening of the furnace wall in spaced relation to the circumferential surface thereof, and it is held in place by a concentric ring 16 fastened to the pipe by means of spokes 17 and fitted in the opening so as to partially line the same.

The annular space 18 between the gas pipe and the opening 6 constitutes the inlet for the stream of air that together with the gases emitted through the passage 12, forms the combustible mixture by which the furnace is heated.

The air may enter the furnace by induced

or natural draft, usually obtained through the medium of a fan or by means of a high stack, or it may be supplied to the inlet surrounding the gas-pipe under artificially produced pressure.

A suitable means to carry the last mentioned method into effect has been illustrated in Figure 2 in which the opening in the furnace wall around the nozzle pipe is covered 10 by a hood 19 at the end of a conduit 20 that connects with the egress opening of a blower 21.

The flow of air to and through the annular inlet may be regulated by means of a damper 15 22, shown in Figure 1, as consisting of a disk slidably supported by the gas-pipe in spaced relation to the outer surface of the furnace wall.

The arrangement of the control valve 20 relative to the header and the nozzle-pipe, as shown in Figure 2, is somewhat different from that of Figure 1, but obviously accomplishes the same purpose.

In the construction illustrated in Figure 3, 25 the nozzle is connected with two sources of gas supply by means of a branched conduit 22. One of the branches, 23, may be connected with one source and the other branch, 24, with a second source and the supply of 30 gas from these sources to the nozzle-pipe may be controlled by a two-way valve 25.

One of the sources may provide a supply 35 of lean gas and the other a supply of richer gas and by proper adjustment of the valve 25 these two gases may be separately supplied to the burner.

It will be understood without further 40 illustration that by proportioning the ports of the valve somewhat differently from those shown in the drawings, the two gases may be supplied to the burner in any desired mixture.

Figure 3 also shows a convenient expedient 45 for the adjustment of the deflector from outside the furnace and if necessary while the burner is in operation.

The deflector slidably supported in the nozzle-pipe as before, is fastened at the end 50 of a rod 26 by means of nuts 27. The rod projects through a stuffing box 28 at the end of the pipe 7 and is held against longitudinal motion by nuts 29 at opposite sides of a brace 40 fastened at the end of the pipe. It will be 55 apparent that by proper manipulation of these nuts the rod may be moved lengthwise to any desired extent and that the width of the gas outlet between the end of the nozzle pipe and the deflector is correspondingly 60 varied.

In the modified construction illustrated in 55 Figure 4, means are provided to supply two different kinds of gaseous fuel either singly or simultaneously through two annular outlets, juxtaposed to intersect the air stream

at substantially the same point and at practically the same angle.

A collar 30 fastened around the nozzle pipe is partially spaced therefrom to provide in conjunction with a flange 34 at the end of the pipe, an auxiliary annular outlet passage 31, in juxtaposition to the passage 12 that connects with the interior of the pipe. 70

Gas from a source of supply separated from that to which the header is connected, 75 is supplied to the space inside the collar by pipes 32 and the connection between these pipes and their source is controlled by a valve 33.

In order to provide for adjustment of the width of the passage 31 between the collar and the flange at the end of the nozzle pipe, the latter may have a telescoping section 35, as shown in the drawings.

By proper adjustment of this section and 80 the deflector, the two passages may be varied in width to any desired extent for the main purpose of adapting the burner to the requirements of different kinds of fuel.

The provision of different kinds of gases 85 either singly or simultaneously to one and the same burner is of more than ordinary importance in furnaces which depend for their gaseous fuel on an unreliable source of supply. For instance in the operation of 90 boilers depending for their fuel supply, on the use of gases produced in blast furnaces, as is the case in most large blast furnace plants, it is practically essential that a source 95 for the supply of a different gas be readily 100 available.

In the operation of blast furnaces, there are 105 periods during which no gas is produced and during which in effect, the furnaces become themselves users of gas. These periods occur, for example, while the furnaces are being tapped and the blast is discontinued. The available gas must during these periods, be 110 used to heat the stoves and the supply of gas to the boilers is in consequence either partially or entirely cut off. It has been customary to provide secondary fuels in order 115 to supply the boilers during the periods of inactivity of the blast furnaces and to either feed these other fuels by hand or install for their use burners different from those employed for consumption of the blast furnace gas.

By the use of the present burner two different gases may be used either singly or together without any different installation, it being evident that the widths of the two annular passages through which the gases are emitted, may be pre-fixed so that the one burner can be employed to supply either gas 125 in the required quantities for proper combustion without further adjustment.

The burner, as shown and described, is not only adaptable for the consumptions of different kinds of fuels singly or together under 130

all conditions, but it provides in a very simple and efficient manner for the complete combustion of the fuel in order to obtain the maximum value of the heat units contained 5 therein.

These advantageous features of the burner are mainly attributable to the production of a combustible mixture by intersecting a stream of air by a current of gas in sheet-like 10 form at substantially right angles to each other and practically at the point of ignition. In this respect the burner differs from those in which the air and the fuel are mixed prior to ignition as in burners of the Bunsen type 15 and from those in which the fuel is supplied through a series of jets between which the air can freely pass.

What I claim and desire to secure by Letters Patent is:

- 20 1. The combination with two sources of fuel-supply, of a burner comprising a nozzle having a flanged end, a deflector spaced from said end to provide an annular outlet, a collar spaced from the nozzle and from the 25 flange to provide a chamber having an annular outlet adjacent the other, and valve-controlled means connecting the nozzle and the chamber with respective sources of supply.
2. The combination with two sources of 30 fuel-supply, of a burner comprising a nozzle having an adjustable flanged section at an end thereof, a deflector spaced from the end of the nozzle to provide an annular outlet, a collar spaced from the nozzle and from the 35 flange to provide a chamber having an annular outlet adjacent the other, and valve-controlled means connecting the nozzle and the chamber with respective sources of supply.
3. The combination of means providing 40 an air duct, a plurality of sources of fuel, a single nozzle connected with said sources for mixing said fuels, an adjustable deflector spaced from an end of the nozzle to provide a passage of variable width for the emission 45 of fuel from the nozzle into the air duct, and means to vary the proportions of said fuels.
4. The combination of means providing an 50 air duct, a plurality of sources of fuel, a nozzle connected with the sources and means on the nozzle for separately spreading the fuels in an outward direction in the air duct in sheet-like form, whereby to be intersected by an air stream in the duct.
5. The combination with two sources of 55 fuel supply, of a burner comprising a nozzle having a flanged end, a duct for conducting a stream of air past said end, a deflector spaced from said end of the nozzle to provide a 60 annular outlet, a collar spaced from the nozzle and from the flange to provide a chamber having an annular outlet adjacent the other, and valve-controlled means connecting the nozzle and the chamber with the 65 sources of fuel supply, said annular outlets being disposed to enter streams of fuel into

the air stream in the duct, whereby to produce an intimate intermixture of both fuels and air beyond the duct.

6. In combination with a furnace having an entrance for the admission of a stream of air, a burner having an egress in said entrance, a plurality of sources of fuel connected with the burner, means for directing currents of fuel discharged through said egress laterally into the air stream, thereby producing an intimate intermixture of fuels with the air within the furnace, and valve means to vary the proportions of said fuels.

In testimony whereof I have affixed my 80 signature.

WALTER G. BAGLEY.
